UNITED STATES PATENT OFFICE

EMERY H. CHASE, OF ADDISON, NEW YORK

DESIGN FOR A VIOLIN

Application filed October 16, 1931. Serial No. 41,413. Term of patent 7 years.

To all whom it may concern:

Be it known that, EMERY H. CHASE, a citizen of the United States of America, residing at Addison, in the county of Steuben, and State of New York, has invented a new, original, and ornamental Design for Violin, of which the following is a specification, reference being had to the accompanying drawings, forming part thereof.

Figure 1 is a top plan view of the violin body showing the design thereon, the violin neck being partly broken away, and Figure 2 is a side plan view of Figure 1 on a reduced scale.

I claim:

The ornamental design for a violin substantially as shown.

In testimony whereof I affix my signature.

EMERY H. CHASE.
